DESIGN FOR A DRESS

Margaret Michelson, New York, N. Y.

Application March 9, 1937, Serial No. 68,086

Term of patent 3½ years

To all whom it may concern:

Be it known that I, Margaret Michelson, a citizen of the United States of America, residing in Manhattan, county and State of New York, have invented a new, original, and ornamental Design for a Dress, of which the following is a specification, reference being had to the accompanying drawing, forming part thereof, wherein,

I claim:

The ornamental design for a dress, substantially as shown.

MARGARET MICHELSON.
